(57) **CLAIM**

The ornamental design for a handle for a tool, as shown and described.

DESCRIPTION

This invention was made with government support under Award No. 2009-33610-19668 awarded by the National Institute of Food & Agriculture. The government has certain rights in the invention.

FIG. 1 is a perspective view of an embodiment of a handle for a tool showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view of a handle for a tool, the broken lines on the generic body of a tool form no part of the claimed design.

The dashed lines shown in FIGS. 1-8 are included for the purpose of illustrating environmental subject matter only and form no part of the claimed design.
